US00D839289S

(12) **United States Design Patent** (10) Patent No.: **US D839,289 S**
 Tuthill et al. (45) Date of Patent: **** Jan. 29, 2019**

(54) **DISPLAY SCREEN WITH GRAPHICAL USER INTERFACE**

(71) Applicant: **Aetna Inc.**, Hartford, CT (US)

(72) Inventors: **Royal Tuthill**, Sea Cliff, NY (US);
Kristen Coletto, New York, NY (US);
Chad Allen, San Francisco, CA (US);
Antony L. Kerz, Rocky Hill, CT (US);
Diana Freeman-Baer, Oakland, CA (US)

(73) Assignee: **Aetna Inc.**, Hartford, CT (US)

(**) Term: **15 Years**

(21) Appl. No.: **29/577,583**

(22) Filed: **Sep. 14, 2016**

Related U.S. Application Data

(63) Continuation-in-part of application No. 15/087,333, filed on Mar. 31, 2016, which is a continuation-in-part of application No. 14/490,111, filed on Sep. 18, 2014.

(57) **CLAIM**

The ornamental design for a display screen with graphical user interface, as shown and described.

DESCRIPTION

FIG. 1 is a front view of a first embodiment of a display screen with graphical user interface showing our new design; and,

FIG. 2 is a front view of a second embodiment of a display screen with graphical user interface showing our new design.

The broken lines showing the display screen and portions of the graphical user interface form no part of the claimed design.

1 Claim, 2 Drawing Sheets
